F. F. WITKUS

PRESSER FOOT CONTROLLING DEVICE

Filed Aug. 11, 1922

Inventor,
Frank F. Witkus,
by L. H. Barrman Atty.

UNITED STATES PATENT OFFICE.

FRANK F. WITKUS, OF NEWPORT, NEW HAMPSHIRE.

PRESSER-FOOT-CONTROLLING DEVICE.

Application filed August 11, 1922. Serial No. 581,118.

To all whom it may concern:

Be it known that I, FRANK F. WITKUS, a citizen of the United States, a resident of Newport, in the county of Sullivan and the State of New Hampshire, have invented an Improvement in Presser-Foot-Controlling Devices, of which the following is a specification.

This invention relates to that class of sewing machines having a presser-foot of the wheel type, which is held against the work in close proximity to the needle, and is so supported that it may not only be lifted vertically from the work, but may also be moved laterally from its normal position adjacent the needle after it has been lifted to a position at one side thereof, so that it will not be in the way of the operator, when it becomes necessary to thread the needle, or make adjustment which would otherwise be interfered with.

Prior to my invention, so far as I am aware, the arrangement, in machines of this character, has been such that it has been necessary for the operator to move the presser wheel by hand from its normal position, when it was desired to thread the needle and to return to said position in the same manner after the needle had been threaded, so that the work of the operator was somewhat delayed.

The object of my invention is to provide a simple and effective means whereby the presser foot may be automatically moved to an inoperative position at one side of its normal position by the action of lifting the presser bar, which carries the presser wheel, to its highest point so that it will be unnecessary for the operator to move the presser wheel out of position by hand, when the needle is to be threaded.

I accomplish this object, in the present instance, by providing means normally actuated to move the presser wheel out of normal position together with means for locking the same in said position, and means for automatically moving said locking means out of operative position arranged to be actuated during the latter portion of the lifting movement of the presser bar.

For a more complete understanding of my invention, reference is made to the accompanying drawing in which:

Figs. 1 and 2 are, respectively, side and front elevations of the presser mechanism of

a sewing machine containing an embodiment of my invention.

Fig. 3 is a sectional view, on an enlarged scale, of the presser bar head illustrating the locking and releasing mechanism.

Fig. 4 is a detail plan view of the presser bar head.

As my invention is applicable to a well known type of sewing machine, only those parts are shown which directly co-operate with the parts to which my invention directly relates.

In the drawing the needle bar casing 1 is shown as provided with the usual vertically movable presser bar 2, which is downwardly spring pressed and adapted to be lifted both by a hand lever in the casing, and by a foot or leg operated lever beneath the machine table, which latter is usually attached to the presser bar, through a chain, or similar means, by means of a collar 3, or other suitable means, attached directly to the bar. A head or block 4 is clamped on the lower end of the presser bar, and carries various attachments, and also carries the presser wheel 5, which is rotatably supported close to the needle, by an arm 6, said arm being mounted to swing outwardly and upwardly about a horizontal axis between a pair of pivot screws 7, threaded in ears on the head 4. A spring 8 is coiled about a pin 9 mounted in the arm, in line with its axis and with its ends respectively engaged by the arm and by the head 4, as shown in Fig. 3, so that said spring, when free to act, will swing the arm from the full line, to the dotted line position of Fig. 2. A right angular shaped locking lever, or latch 10 is mounted on the head 4 by means of a pivot 11, the arm 10^a of said lever extending beneath the head and having a rounded projection 10^b at its end, which is adapted to engage the front side of a portion of the arm 6 adjacent the lower edge thereof, said arm being normally held against said lower edge by the action of a spring 12, which is arranged to engage the other arm 10^a of the lever. With this arrangement, when the arm 6 is in normal position, it will be held by the projection 10^b against outward and upward swinging movement by the spring 8. As the surface portion of the projection 10^b, which engages the arm 6, is somewhat rounded, the arm 6 may be forced by hand out of engagement with the projection 10^b, so that the

wheel will be held in the dotted line position of Fig. 2, and as the opposite side of said projection is also rounded, when the arm 6 is manually pressed there against, in returning the same to normal position, the arm 10^a will yield and act as a latch to lock the arm 6 in the latter position. A stop screw 13 is provided in the arm 6 which is brought into engagement with the head 4 as the presser 10 wheel is swung into normal position, in which position the work engaging face of the wheel is at the inner side of the perpendicular line through the axis about which the arm 6 swings, so that, when the wheel is 15 pressed against the work, the tendency is to swing the arm in the direction to press the stop screw 13 against the head.

A rod 14 is slidably mounted in the head 4, and rests at its lower end, on the arm 20 10^a, the upper end portion thereof projecting above the head 4 to such an extent, that, when the presser bar is raised to its highest point, the upper end of the rod 14 will engage the under side of the casing 1 just before the highest point is reached, so that, during the remainder of the lifting movement, the rod will be held against movement, causing the arm 10^a of the latch to be swung away from the head 4 sufficiently 30 to disengage it from the arm 6 and permit the spring 8 to swing the latter up to its inoperative position.

With this arrangement, when the presser is only lifted to a sufficient extent to enable 35 the operator to shift the position of the work, the latch will not be disengaged, but, when the operator, for example, wishes to thread the needle, the presser bar will be raised to its fullest extent and the wheel will be 40 automatically swung out of the way of the operator. Before the presser bar is lowered, the arm 6 will be pushed back to the normal position by hand.

A small push button 15 may be provided 45 on the arm 10^a, which if pressed will release the latch, but ordinarily this will not be employed.

I claim:

1. In a sewing machine, a presser bar movable vertically between predetermined limits and having a presser-foot at its lower end, means permitting lateral movement of said foot relatively to said bar between a normal position and an inoperative position at one 55 side of said normal position, means nor-

mally acting to retain the foot in said normal position, and means for automatically moving the foot to said inoperative position when the bar is raised to a predetermined extent.

2. In a sewing machine, a presser bar movable vertically between predetermined limits and having a presser-foot at its lower end, means permitting lateral movement of said foot, relatively to said bar, between its normal position and an inoperative position at one side of said normal position, means normally acting to retain said foot in its normal position, and automatically operated means for moving said foot from its normal to its inoperative position during the latter portion of the upward movement of the presser-bar.

3. In a sewing machine, a presser bar movable vertically between predetermined limits and having a presser-foot at its lower end, means permitting lateral movement of said foot, relatively to said bar, between its normal position and an inoperative position at one side of said normal position, means normally tending to move the foot from its normal to its inoperative position, a locking device arranged to hold the foot in its normal position and means arranged to be automatically operated to move said locking device to release the foot and permit movement thereof to its inoperative position, when the bar is lifted to the upper limits of its movement.

4. In a sewing machine, a presser bar movable vertically between predetermined limits and having a presser-foot at its lower end, means permitting lateral movement of said foot, relatively to said bar, between its normal position and an inoperative position at one side of said normal position, a spring normally tending to move the foot from its normal to its inoperative position, a latch for retaining the foot in its normal position against the action of said spring, a fixed abutment, and means carried by said bar, arranged to engage said abutment during the latter portion of the upward movement of the bar and to be relatively moved to release said latch, to permit the spring to move the foot to its inoperative position.

In testimony whereof, I have signed my name to this specification.

FRANK F. WITKUS.
